GRID FOR ICE TRAYS

Robert Lay Hallock, Larchmont, N. Y.

Application June 9, 1937, Serial No. 147,238

13 Claims. (Cl. 62—108.5)

1

My invention relates to grids for ice trays. The object is to provide an improved grid which is effective in operation and readily manufactured.

My improved grid is shown in preferred form in the accompanying drawings, whereof:

Fig. 1 is a longitudinal cross-section through an ice cube tray, showing the grid therein, in elevation;

Fig. 2 is a plan view of the grid;

Fig. 3 is an elevational cross-sectional view taken on line 3—3 of Fig. 2;

Fig. 4 is a bottom view, partly in section, taken on line 4—4 of Fig. 3;

Fig. 5 is a vertical sectional view taken on line 5—5 of Fig. 3;

Fig. 6 is a vertical sectional view taken on line 6—6 of Fig. 3;

Fig. 7 is an elevational view of a transverse grid wall or wall piece;

Fig. 8 is an elevational view of a longitudinal wall piece;

Fig. 9 is an end view;

Fig. 10 shows the grid bowed;

Fig. 11 shows how the lever is connected to the spring member;

Fig. 12 is taken on the line 12—12 of Fig. 10;

Fig. 13 is a plan view of a modified form of grid embodying the invention;

Fig. 14 is an elevational view of an element of the grid shown in Fig. 13; and

Fig. 15 is a sectional view taken on the line 15—15 of Fig. 14.

The grid shown in Figs. 1—12 includes a U-shaped spring member 10 which extends longitudinally of the tray 11 and touches the bottom and end walls. Member 10 is formed with shoulders or ears 12 in which are transversely spaced apertures or holes 13. Member 10 is provided with long apertures or slits 14. Slits 14 are longitudinally aligned and are in the plane of the longitudinal wall or dividing member of the grid. The apertures 13 are in the planes of the transverse grid walls. Member 10 may be stamped out of flat stock and then bent to form and tempered. It may be made of suitable steel stock. It is looped at the ends to provide journals or eyes for pivot pins 15 on which are mounted levers or handles 16.

The transverse walls 17 are alike and are shown in Fig. 7. They may be punched from flat stock and may be, for example, made of steel, aluminum, brass or other metal, or even non-metallic material, treated electrically, chrome or nickel plated, and/or waxed. I prefer stainless steel.

2

Walls 17 extend the width of the tray and are apertured at 18 and 19, that is, at the top and bottom center, to provide recesses for reception of projections on the longitudinal wall pieces.

Wall 17 is cut at 20 to straddle spring bar 10. The intermediate projections 21 slip into apertures 13. Projections 21 are upset (like heading a rivet) in apertures 13 to position wall 17 on the spring bar. The apertures 13 may be tapered outwardly downwards, as for a countersunk rivet head. It is desirable that the bottom edges of wall 17 and the bottom of spring member 10 and the bottoms of projections 21 be aligned and substantially in contact with the bottom of the tray. On punching, projections 21 are preferably somewhat extended beyond the bottom edge of the wall in general to give additional material to permit the upsetting.

The longitudinal wall pieces are of two kinds, 20 the end pieces 24 and the intermediate pieces 25. One wall member 25 is shown in Fig. 8. These pieces may also be formed from flat stock in a punch press. Wall 25 has offset bottom projections 26 which fit into apertures 19 of transverse walls 17. The projections are oppositely offset so that projections on adjacent wall pieces 25 can be held in the same aperture 19 in overlapping relation. Similarly, offset projections or extensions 27 are provided at the upper corners of walls 25. These projections are hook-shaped to provide movement limiting abutments. The necks of projections 27 are positioned in apertures 18. The ends extends below the bottoms of recesses 18. As in the case of projections 26, projections 27 on adjacent walls 25 overlap in the same recess 18. The lower parts of walls 25 have central extensions 28 which extend into slits 14.

End wall pieces 24 are made to fit the spring bars 10. They are provided with projections 26 and 27 on one side. The other side sets into slotting in spring bar 10. The pin 15 passes through plate 24.

In assembling the grid, the projections 27 of walls 25 are first slipped over walls 17 and projections 26 slid into recesses 19, after which projections 21 may be pushed into apertures 13 and upset.

Levers 16 are provided with hand grips 30 and abutments 31 (Fig. 11) which, on lifting levers 16, contact the outside of spring bar 10 at points below the axis of the levers, whereby, on pushing the levers further apart, the spring bar 10 is bowed, as shown in Fig. 10. End walls 24 are provided with upstanding parts 32 which constitute rests for levers 16 in lowered positions.

It will be seen that the walls 25 are held in position because the projections 26 are held between walls 17 and spring bar 10. Projections 27 also act as positioning guides. The walls are tied at their lower parts and are otherwise free for relative movement, though limited by the length of necks of the projections 27. Fig. 10 illustrates how the hook-like projections 27 limit the spread or flare of the wall parts. It will be seen that there is a uniform distribution of bending movement in the grid as the levers are spread.

It will also be seen that the parts of spring bar 10 to the sides of the slits are bowed and that their middle parts move upwardly to exert a shearing force between the wall 25 and the ice block attached thereto.

Levers 30 may be, and are in the form shown, made to bear against the tray in their initial movement to cause the grid with ice cubes attached thereto to be removed from the tray. The levers may press the ends of the tray from the ice block to peel the tray from the ice block.

The grid illustrated in Figs. 13 to 15 differs from that shown in the preceding figures in that the transverse walls are double, being made up of separate plates 40 and 41 which are placed side by side and are mounted as a unit in apertures 13. Parts 40 and 41 are spot-welded at 43 near the outer ends and not at intermediate points. If sheets 40 and 41 are made of aluminum or similar metals it may be desirable to wax or otherwise treat the contacting surfaces. This is not necessary if stainless steel is used having at least a medium polish.

When the ice is frozen it sticks to the walls 40 and 41. As the levers 16 are spread apart the grid is flared and upper parts spread apart. The least resistance to spreading is at the inside contact surfaces between walls 40 and 41. Consequently these walls tend to separate at the top of the grid. Since they are held at 43, the ends will stay together as the center portions spread due to adhesion to the ice. Thus there is a progressive separation of the ice and walls 40, 41 beginning at the outer ends and the walls are gradually peeled away from the ice working inwardly from the outer edges. The walls thus bow apart. However, as the walls 40 and 41 are separated, projections 27 approach each other. When the walls 40 and 41 are separated a certain amount, the projections 27 contact the walls and, as the grid is further flexed, the projections 27 pull the walls 40, 41 together again, thus pulling these walls away from the ice blocks. Thus walls 40 and 41 are first spread apart due to sticking to the ice, and then their movement is reversed and they are brought together due to the prongs 27 approaching each other. Thus the ice blocks are removed from the transverse walls. The bowing of the parts of the spring member between projections 12 causes an upward compressive force on the ice block, shearing it from the longitudinal wall.

It will be understood that variations may be made within the ambit of the invention.

What I claim is:

1. In a grid for ice trays, a distortable longitudinal member, individual wall pieces mounted on the longitudinal member, and means comprising parts having a predetermined extent of relative movement and abutting when moved said predetermined extent for limiting the relative movement of the individual wall pieces on distortion of the longitudinal member.

2. In a grid for ice trays, a distortable longitudinal member, individual wall pieces mounted on the longitudinal member, and overlapping extensions on some of the wall pieces for limiting their relative movement on distortion of the longitudinal member.

3. In a grid for ice trays, a spring member having apertures, wall pieces having projections loosely positioned in some of said apertures, and other wall pieces having projections fixed in other apertures and holding the first-mentioned wall pieces in place.

4. In a grid for ice trays, a longitudinal spring member having slits, longitudinal wall pieces loosely mounted to in part project into said slits, and transverse wall pieces directly mounted on the spring member, said longitudinal wall pieces having overlapping projections for holding the longitudinal wall pieces in position and limiting movement thereof.

5. In a grid for an ice tray, a flat wall, a crossing wall having a slit, at least a part of the flat wall passing in or through the slit, the flat wall and crossing wall being tied together beyond the ends of the slit, and means to bow the crossing wall to exert shearing force on ice attached to the flat wall.

6. In a grid for an ice tray, a longitudinal single-piece spring member, one or more levers mounted on said spring member, and transverse and longitudinal dividing members mounted on said spring member, said spring member extending longitudinally along edges of the longitudinal wall members and being bent at its end so as to be of generally U-shape.

7. In a grid for an ice tray, a longitudinal single-piece spring member of generally U-shape, one or more levers mounted on said spring member, and dividing members mounted on said spring member and having overlapping and interfitting projections and recesses receiving said projections for positioning and limiting movement thereof.

8. A grid adapted to be bowed having double-walled members, means to spread ice pieces stuck to said walls to spread the walls, and means to move the walls together to remove them from the ice pieces.

9. A grid having sets of contacting transverse walls, longitudinal wall members extending between said transverse walls, means to hold the parts so that the sets of transverse walls may be spread in flaring fashion, the transverse walls of a set being fastened in part and not fastened in part, so as to separate on flaring the grid with ice formed thereon, and hook-like extensions on the longitudinal wall members passing across the transverse walls and adapted to pull transverse walls of a set together.

10. A grid having a longitudinal spring member with apertures therein, sets of contacting transverse walls held in said apertures, the walls of a set being secured at outer points, and hook-like members passing over the sets of transverse walls in pairs to limit separation of and pull together the walls of a set.

11. In a grid, structure for mounting pocket forming walls thereon, said structure being adapted to be bowed, walls mounted on said structure in a manner to separate, and means to reverse the relative movement of said walls on bowing the grid in one direction.

12. A backbone for a grid comprising a generally U-shaped piece of relatively narrow flat

resilient material having a plurality of slits extending longitudinally thereof adapted to receive thin wall members.

13. The combination of an ice tray and a grid removably disposed therein and forming therewith a series of ice cube forming compartments of predetermined size, said grid comprising a longitudinal partition and a series of spaced transverse partitions extending therefrom and forming therewith the walls of said compartments, the longitudinal partition being made up of a series of sections, means connecting said sections together to be movable through a limited arc with respect to each other, means other than the connecting means for limiting such movement of the sections, each of said transverse partitions being so related to one of said sections that the movement of said section

causes an enlargement of the corresponding ice cube compartment and a breaking of the ice bond between the ice cubes formed therein and the grid.
